[57] CLAIM

The ornamental design for a housing for a data connector, as shown and described.

DESCRIPTION

FIG. 1 is a top perspective view of the housing for a data connector of the subject invention;

FIG. 2 is a right side elevation view of the housing for a data connector of FIG. 1. The left side elevation view is a mirror image of the right side elevation view;

FIG. 3 is a top plan view of the housing for a data connector of FIG. 1;

FIG. 4 is a bottom plan view of the housing for a data connector of FIG. 1;

FIG. 5 is a front elevation view of the housing for a data connector of FIG. 1; and,

FIG. 6 is a rear elevation view of the housing for a data connector of FIG. 1.

The broken line drawings of interior details in FIGS. 1, 5 and 6 are for illustrative purposes only and form no part of the claimed design.
